DESIGN FOR AN INFANT'S PLAY PEN

Earl D. Boisselier, Glen Ellyn, Ill., assignor to Sears, Roebuck and Co., Chicago, Ill., a corporation of New York

Application July 27, 1945, Serial No. 121,011

Term of patent 14 years

(Cl. D34—5)

To all whom it may concern:

Be it known that I, Earl D. Boisselier, a citizen of the United States of America and a resident of Glen Ellyn, county of Cook, and State of Illinois, have invented a new, original, and ornamental Design for an Infant's Play Pen, of which the following is a specification, reference being had to the accompanying drawing, forming a part thereof.

The drawing is a perspective view of an infant's play pen, showing my new design.

I claim:

The ornamental design for an infant's play pen, substantially as shown.

EARL D. BOISSELIER.
